UNITED STATES PATENT OFFICE.

WINTHROP L. JACOBS, OF EAST ORANGE, NEW JERSEY, ASSIGNOR TO THE
HARTFORD CARPET COMPANY, OF HARTFORD, CONNECTICUT.

DESIGN FOR A CARPET.

SPECIFICATION forming part of Design No. 12,505, dated October 4, 1881.

Application filed August 15, 1881. Term of patent 3½ years.

To all whom it may concern:

Be it known that I, WINTHROP L. JACOBS, of East Orange, in the county of Essex and State of New Jersey, have invented a new and original Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

A is a circular figure, resembling an open flower with serrated edges. B is a circular flower-like figure set on an angular stem. a is a figure resembling a half-rosette with a leaf projecting from its top. o is a figure resembling a cornucopia in shape and made up of small figures. D is a flower-like figure with open spray leaves. G is a figure one part of which appears on each side of the design, and consists of a rosette-like center surrounded by leaf-like figures. H is also a figure of which one part appears on each side of the design. It is circular in form, and has projecting from one side a branch with flowers thereon. b is flower-like figure, resembling a tulip set on a

stem. C is a flower-like figure with projecting open leaves. p resembles a circular flower set on a stem. h is a figure resembling a leaf with buds thereon. n is a figure resembling a flower projecting into the design. E is shaped like a cornucopia and made up of a variety of small figures. d is an oval flower-like figure. i is a circular figure. e is a figure resembling a branch with buds upon it. F is a figure resembling a cross with leaves projecting from its ends. k is a branch with buds upon it, and m is another somewhat similar branch.

The whole effect of the design is that of a vine, branch, or stem running irregularly across a background composed of small oval figures with rectangular centers, the vines or branches bearing upon them at intervals the various figures described.

I claim—

The design for carpets, consisting of the figures A, D, G, o, a, b, H, C, p, n, h, i, k, E, d, e, B, F, and m, substantially as shown.

WINTHROP L. JACOBS.
